UNITED STATES PATENT OFFICE.

HARRY LYON, OF HOLBROOK, MASSACHUSETTS, ASSIGNOR TO PERLEY E. BARBOUR, OF QUINCY, MASSACHUSETTS, DOING BUSINESS AS BARBOUR WELTING COMPANY, OF BROCKTON, MASSACHUSETTS.

GOODYEAR WELTING.

Application filed January 7, 1928. Serial No. 245,208.

This invention relates to the manufacture of welting and more particularly to welting for use in Goodyear welt shoes.

Heretofore it has been the practice to sever 5 a fillet of welting leather and then separately groove and bevel the two strips thus obtained. It is highly important that the characteristic features of the inner edge of the welting, i. e. the groove and the various forms of bevel, 10 be definite and unvarying in position and dimensions throughout the length of the strand. Such a result is impossible to obtain using the welt grooving and beveling machines that are available commercially because of the ununiform 15 texture of the stock forming the strip being operated upon. Some parts of the hide are very soft and others very firm and in a strip of fifty to one hundred yards in length these differences in texture will be repeated 20 many times. While the beveling knife will naturally cut through the firm stock at a proper distance from the groove to provide sufficient leather for a solid and strong anchorage of the inseam, when a soft spot is 25 reached the leather will crowd or jamb in front of the knife because of its lack of resistance, whereupon the knife digs and cuts the bevel on too far. The anchorage thus is lost and a weakness is developed that is bound to 30 make itself known by a weak inseam when such welting is built into a shoe. To guard against this it is the present practice to make an allowance at the inner side of the groove, i. e. the groove is cut further away from the 35 inner edge than is dictated by good practice, but this reduces the width of the grain extension and makes the welting less desirable or requires a wider strip to compensate which means more leather, greater initial 40 cost, and more waste at the inseam trimming operation.

The object of the present invention is to perfect the manufacture of Goodyear welting by an improved method of forming the 45 groove and bevel that insures a groove of uniform distance from the inner edge of the completed strand, whatever variations there may be in the texture of the leather being operated upon, and consequently a uniform grain extension of maximum width.

To the achievement of this object the invention comprises the novel method of manufacturing Goodyear welting hereinafter described and then particularly defined by the

appended claims, an understanding of which 55 will be aided by the accompanying drawings, in which:

Figure 1 is a view, in perspective, of a portion 60 of a fillet of welting leather from which two welt strips are to be produced;

Fig. 2 is a view, in perspective, of the fillet 65 of Fig. 1 after grooving for both of the welt strips and partly severing;

Fig. 3 is a view, in perspective, of the fillet 70 of Fig. 1 in reversed position after beveling both of the strips and completely severing; and

Fig. 4 is a view, in perspective, of one end 75 of a strand of the completed Goodyear welting.

As illustrated by the drawings the process may start with a fillet 10 of a width for producing two welt strips (or a multiple of two) of the kind required, for example if the completed strand is to be sold as half-inch welting the fillet is then one inch wide, and so on. The thickness of the fillet may vary as desired.

The flesh side of the fillet 10 is then operated upon by a triplex knife characterized by 80 a flat central blade for making the central incision 12, that is flanked by two curved blades for making the two grooves 14 and 16. Preferably the knife is a drag knife, or dead, while the fillet is fed continuously past it. 85 The relation of the three blades is such that all three cuts are made at the same time, while the two grooves are made at equal distances from the central cut 12 and, therefore, also at equal distances from the two edges of the 90 fillet 10. The three blades of the knife are in fixed relation to each other so that the central blade supports the stock at each side thus insuring two grooves 14 and 16 always in an unvarying position relative to each other 95 and to the flesh sides of the two welt strips that are being formed by the central cut 12. The central blade of the triplex knife is so proportioned that, although the two side blades cut completely formed grooves, it does 100 not completely sever the fillet leaving it joined by a short integral portion 18 of the grain. Provision is made for holding the fillet 10 down upon the knives for receiving the full accuracy of their cuts therein, and 105 also for guiding the fillet and preventing it from wandering while receiving the cuts.

It will be observed that both grooves and

the fillet dividing cut are made simultaneously and hence the width, or margin 20 (Fig. 4), of stock between the fillet dividing cut and the inner edge of each groove must be uniform for each welt strip throughout the entire length of the fillet regardless of its texture. Thus the curved blades may be set to give the least margin 20 (Fig. 4) compatible with the required strength for anchorage of 10 the inseam, thus to secure the greatest possible width of grain extension 22 (Fig. 4).

The final step in the manufacture of the 15 welting consists in forming both bevels 24 and 26 (Fig. 3) simultaneously and at the same time completely dividing the fillet 10 into two welt strips. Preferably, but not necessarily, the position of the fillet is reversed so that its grain side may be pressed down in position to be cut centrally by a 20 channelling knife. For producing the plain bevel illustrated, this knife has a V-shaped edge, the two blades being placed at any angle that may be required for cutting the two bevels 24 and 26. The depth to which 25 the channeling knife cuts is always greater than the thickness of the unsevered grain material 18 at the center of the fillet so that the formation of the channel cut necessarily removes this connecting element between the 30 two strips. Thus two accurately grooved and beveled welt strands 28 and 30 result from this second cutting operation.

In sewing the inseam the needle of the 35 welter should pierce the grain side of the welt at the angle 32 (Fig. 4), or at least not outside of this point, so as to preserve the grain extension 22. The cutting of both bevels before the fillet is severed into two strips, permits a setting of the beveling knife 40 that will accurately determine such a relation of each bevel to its respective groove as will insure a piercing by the welter needle substantially through the angle 32, because the central portion of the fillet stock that is 45 being removed is firmly held and prevented from spreading in front of the knife, or crowding to either side to spoil the accuracy of the cut.

By practicing the method of this invention 50 a groove that is a uniform distance from the inner edge of the welt strip is guaranteed notwithstanding a variation in texture of the stock from soft to hard and vice versa. This is due to cutting both grooves at the same 55 time and always in the same place throughout the continuance of the cutting operation, and also both bevels at the same time. I believe that I am the first to discover the importance of this in manufacturing welting.

50 Those skilled in the art will understand from the foregoing description that any width of fillet may be used in starting production of the welt strands, this being mere duplication, and that the size or shape of the 65 grooves and bevels and their relation to the

dimensions of the welt strip, and to each other, may be varied within reasonably wide limits to suit the desire of any shoe manufacturer, or the needs of the particular type of Goodyear welting that is to be produced.

70 While "leather" is herein named as the material being operated upon this nomenclature is not intended as a limitation as to the material which might be used. On the contrary the method which I desire to protect is 75 independent of material except that leather is found to be particularly advantageous in the manufacture of fine Goodyear welting.

Having thus described the novel method 80 and one mode of practicing it when employing its underlying principle, yet recognizing that some modifications and changes may be made without departing from its spirit and scope, what is claimed as new, is:—

1. The method of making welting which 85 includes the steps of partially severing a fillet of welting material through its thickness into two welt strips, and cutting two grooves, one for each strip, and then cutting two bevels, one for each strip, at one operation and simultaneously completing the severance of the fillet.

2. The method of making welting which 90 includes the steps of cutting centrally and longitudinally of a fillet of welting material part way through the thickness thereof from one face, cutting a groove in said face at each side of an parallel to said central cut, and cutting a V-shaped channel longitudinally in 95 the other face of said fillet the apex of said V-shaped channel being at the center of said fillet and farther from the channeled face than the thickness of the unsevered material left by the first named central cut.

3. The method of making welting which 100 includes the steps of partially severing a fillet of welting material into two welt strips by a central incision in one face thereof, and cutting a groove at each side of said incision while the intervening stock is supported by the incising blade, and completing 105 the two welt strips by a central cut in the opposite face of the fillet deep enough to complete the severance of the fillet.

4. The method of making welting which 115 comprises incising the flesh face of a welting leather fillet centrally to a depth which leaves the two partially severed strips still connected by the grain of the leather and simultaneously cutting two grooves in said flesh face one at each side of said incision, and finally simultaneously cutting two opposed and joined bevels centrally on the grain face of said fillet the depth of the beveling cut being such that said grain connection between the two welt strips is included in the material of the triangular string that is removed.

5. The method of making welting which 125 comprises cutting two longitudinal grooves 130

in the flesh side of a welting leather fillet and simultaneously incising the fillet centrally between said grooves from the flesh to the grain but not through said grain, and then 5 removing said unsevered grain by a central longitudinal channel cut from the grain to the flesh.

6. The method of dividing a welting fillet into two strands of Goodyear welting which 10 consists of double grooving one face thereof longitudinally while simultaneously cutting partially through its thickness centrally and midway between said grooves, and then cutting 15 a string of triangular cross-section centrally from the opposite face thereof the altitude of the triangle being greater than the thickness of the unsevered material of the fillet.

7. The method of making two Goodyear 20 welting strands simultaneously which consists in feeding a welting fillet first past a triplex knife that cuts two parallel grooves

and an intermediate slit centrally in one face thereof while gaging said knife for operation on said fillet so that the grooves are completely formed but the slit ends short of the opposite face of the fillet, and then past a V-shaped knife while gaging said knife to cut centrally in said opposite face of the fillet to a depth sufficient to intersect said slit. 25

8. The method of making welting which includes the steps of cutting centrally and longitudinally of a fillet of welting material part way through the thickness thereof from 30 one face, cutting a groove in said face at each side of said central cut, and cutting a channel longitudinally in the other face of said fillet opposite said central cut, said channelling cut having a depth greater than the 35 thickness of the material left unsevered by said central cut. 40

HARRY LYON.
